UNITED STATES PATENT OFFICE

ALBERT MOSHEIM, OF NEW YORK, N. Y., ASSIGNOR TO HOUSE OF TRE-JUR, OF NEW YORK,
N. Y., A CORPORATION OF NEW YORK

DESIGN FOR A CAKE OF SOAP

Application filed December 27, 1932. Serial No. 46,633. Term of patent 7 years.

To all whom it may concern:

Be it known that I, ALBERT MOSHEIM, a citizen of the United States, and a resident of New York city, in the county of New York and State of New York, have invented a certain new, original, and ornamental Design for a Cake of Soap, of which the following is a specification, reference being had to the accompanying drawing, forming part thereof.

Figure 1 is a plan view of a cake of soap illustrating my new design.

Figure 2 is a side elevation of the cake of soap; and

Figure 3 is an end elevation thereof.

I claim:

The ornamental design for a cake of soap substantially as shown.

Des Moines, Iowa, November 15, 1932.

ALBERT MOSHEIM.
